(57) **CLAIM**

The ornamental design for a magnetic component for mobile holder, as shown and described.

DESCRIPTION

FIG. 1 is a first perspective view of a magnetic component for mobile holder showing my new design;
FIG. 2 is a second perspective view thereof;
FIG. 3 is a top view thereof;
FIG. 4 is a bottom view thereof;
FIG. 5 is a front view thereof;
FIG. 6 is a back view thereof;
FIG. 7 is a left side view thereof; and,
FIG. 8 is a right side view thereof.
